(57) **CLAIM**

The ornamental design for a circular jewelry display pyramid, as shown and described.

DESCRIPTION

FIG. 1 is a perspective view of a circular jewelry display pyramid.

FIG. 2 is a front elevation view of a circular jewelry display pyramid. The back view being identical to the front view.

FIG. 3 is a side elevation view thereof, the opposite side view being the same.

FIG. 4 is a top view thereof; and,

FIG. 5 is a bottom view thereof.

The broken lines are for the purpose of illustrating the environment of the design only and form no part of the claimed design.
